UNITED STATES PATENT OFFICE.

JAMES G. DAVIS, OF BUFFALO, NEW YORK.

MOLD FOR MAKING BUILDING BLOCKS.

Application filed April 28, 1920. Serial No. 377,371.

To all whom it may concern:

Be it known that I, JAMES G. DAVIS, a citizen of the United States, residing in the city of Buffalo, in the county of Erie and 5 State of New York, have invented new and useful Improvements in Molds for Making Building Blocks, of which the following is a specification.

This invention relates to a mold for making sections or blocks of gypsum concrete or similar plastic material for use in constructing floors and ceilings of buildings mainly of reinforced concrete.

The particular building block which is 10 designed to be made by this mold is generally of L-shape form and comprises a horizontal plate and a vertical flange arranged at one end of the plate.

It is the object of this invention to provide 15 a mold whereby such building blocks may be made quickly, economically, easily, accurately and with a minimum amount of labor.

In the accompanying drawings:

20 Figure 1 is a vertical longitudinal section of the preferred form of mold embodying my invention. Figure 2 is a fragmentary vertical longitudinal section showing the mold adapted for forming a building block 25 with a shorter flange. Figure 3 is a vertical transverse section taken on line 3—3, Fig. 1.

Figures 4 and 5 are perspective views of a co-operating pair of building blocks designed to be made by my improved mold.

30 Figure 6 is a fragmentary section of a floor and ceiling construction containing building blocks made in a mold containing my invention. Figure 7 is a top plan view of the mold.

35 Similar characters of reference refer to like parts throughout the several views.

A floor and ceiling construction containing 40 building blocks or sections made on the mold forming the subject of this invention 45 comprises a plurality of upper blocks or sections and a plurality of lower blocks or sections. Each lower block comprises a comparatively long lower horizontal plate 10 and an upstanding flange 11 arranged at one 50 end of the plate, and each upper block comprises a comparatively short upper horizontal plate 12 and a depending flange 13 at one end of the upper plate. In the assembled condition of a plurality of such blocks the 55 unflanged end of each lower plate engages

the flanged end of an adjacent lower plate and each upper block has its unflanged end engaging the upper end of the upstanding flange of the companion lower block while its depending flange engages with the upper 60 side of the horizontal plate of the respective lower block and at a distance from the upstanding flange of an adjacent lower block, thereby forming a channel between the adjacent upstanding and depending flanges. A 65 mass of concrete is spread over these blocks when assembled which forms a horizontal slab 15 over the blocks and vertical beams or girders 16 on the underside of the slab and in the channels between the opposing 70 flanges of the blocks. The unflanged edge of the upper horizontal plate is preferably beveled, as shown at 120, to avoid the formation of a sharp corner which would be likely to be broken off during shipping or installation. The unflanged end of each lower horizontal plate is held in place by providing the same with a beveled face 17 engaging with a correspondingly beveled face 18 on the 75 flanged end of the adjacent lower plate and the two flanges which form a channel between them have their opposing outer surfaces 19, 20 constructed so that this channel is comparatively narrow at a place between its top and bottom and widens upwardly and 80 downwardly from said narrow part so that the beam formed therein will be of substantially hour-glass form in cross section and thus support said blocks when the mass of concrete becomes hard. The unflanged ends 85 of the lower plates are further supported by means of anchors 21 embedded at their lower ends in that part of each lower plate forming the bottom of a channel and arranged with its upper part in the concrete of the beam 90 so that when the latter is dry the anchors embedded therein will firmly support the lower plate. The upper part of each anchor is preferably constructed to form a chair or 95 seat for reinforcing rods or bars 22 which in the finished condition of the ceiling and floor are embedded in the lower part of the concrete forming the beam and thus strengthen the same in a well known manner. These 100 anchors are preferably constructed of wire 105 and secured to the top of the lower plate so that they can be folded against the flat surface of the plate for convenience in shipping and then bent up into position for use.

For the purpose of further interlocking 110

- the concrete of the beam with the flanges of the blocks the flanges are provided in their lower parts with notches 23 which receive the concrete when poured into the channels.
- 5 To prevent the upper blocks from being broken when workmen walk upon the same while erecting the building, each of the upper blocks is preferably provided on the underside of its horizontal plate with a plurality of longitudinal ribs 25, 250. The flanges of the upper and lower blocks are also provided on their inner sides with a plurality of upright ribs 24, to strengthen the same.
- 10 The mold shown in Figs. 1, 3 and 7, is designed for making the upper building blocks but the same is capable of making the lower blocks and other forms of L-shaped blocks by suitably constructing the 20 surfaces forming the cavity which receives the plastic material. In these figures, 40 represents the stationary main frame of the mold which may be of any suitable construction. 26 represents a stationary horizontal bottom board or plate which is mounted on the main frame and the upper side 27 of which is horizontal and flat and provided with a plurality of longitudinal grooves 28 so as to form the underside of 30 the horizontal plate of an upper building block shown in Figs. 4 and 6. The unflanged edge of this plate is formed by a rear end mold bar 29 arranged transversely over the rear end of the bottom plate and 35 having its front edge 30 constructed to form the unflanged beveled edge of the horizontal plate of the building block. For this purpose this bar has its upper front corner 31 constructed to overhang forwardly and 40 its rear edge is pivotally connected by hinges 32, or otherwise, to the bottom plate so that the rear end bar can be lowered and raised into and out of its operative position.
- 45 Extending downwardly from the front end of the top plate is an inner upright supporting wall 33 which is fixed to the main frame. On its front side this inner wall is provided with a removable platen 34 the face of which is provided with upright cleats 35 so that the same forms the inner ribbed surface of the flange of a building block. This platen is removably secured by screws 36 or otherwise to the 50 wall 33 so that the same may be replaced by a platen of a different pattern, as will be explained further on.
- 55 Projecting forwardly from the lower edge of the inner wall 33 is a horizontal flange 37 which forms the outer edge of the flange on the building block.
- 60 In front of the inner wall 33 is arranged an upright outer wall 38 which is movable toward and from the inner wall preferably 65 by pivotally connecting the lower ends of

these walls by hinges 39, as shown in Figs. 1 and 2 so that the outer wall can swing inwardly and outwardly. On its inner side this outer wall is provided with an upright platen 40 which is detachably connected therewith by screws 41, or otherwise and had its face constructed to form the pattern for the front side of the building block flange.

70 42 represents two upright side plates 75 which are arranged lengthwise along opposite sides of the bottom plate, rear end bar and outer and inner walls and having their upper parts projecting above the longitudinal edges of the bottom plate and their front parts projecting across the space between the pattern faces of said outer and inner walls. These side walls may be pivoted at their lower edges to the sides of the main frame by hinges 43 or otherwise 80 so as to permit the same to swing inwardly and outwardly into their operative and inoperative positions.

85 In the operative position of the several parts of the mold the rear bar is swung 90 downwardly, the outer wall is swung rearwardly and the side plates are swung inwardly into the positions shown in Figs. 1, 3 and 7, thereby forming a mold cavity 95 between these several members corresponding to the L-shaped building block it is desired to make. After the mold sections have been thus assembled the plastic mass from which the building blocks are to be made, such for instance as gypsum and saw dust 100 mixed with water, is introduced into the mold cavity until the same is filled after which the same is struck off level with the upper surfaces of the outer wall, side plates and rear bar, and then left to dry and harden. When the block has become sufficiently hard to permit of handling, the same is removed from the mold and set away to finish its hardening sufficient for using the same 105 in building a floor or ceiling. To permit the easy removal of the finished block from the mold without injuring the same the attendant first raises the rear edge bar, swings the outer wall forwardly and swings the side-walls outwardly, thereby freeing the molded building block on its front side, rear edge and lateral sides and permitting easy removal thereof without liability of damaging the same. After the block has been removed the movable parts of the mold are again restored to their normal positions preparatory to making another block.

110 Various means may be employed for moving the movable members of the mold into and out of their operative positions but those shown in the drawings have been 115 found satisfactory in practice and therefore preferred. As there shown the shifting means comprise a main operating lever 44 arranged horizontally and lengthwise in 120

125

130

the lower part of the main frame and pivoted on the rear part thereof by a pin 45 so as to turn vertically, a rock arm 46 projecting rearwardly from the rear end bar 5 and connected by an upright link 47 with the rear arm of the main lever, an auxiliary or intermediate front lever 48 pivoted on the upper front part of the main frame to swing vertically and provided on its upper 10 arm with a slot 49 which receives a pin 50 on the outer mold wall while its rear arm is connected by an upright link 51 with the front arm of the main operating lever, and a pair of inclined links 52 which diverge upwardly transversely of the mold and are pivotally connected at their lower ends with opposite sides of the front arm of the main lever while their upper ends are pivotally connected with the side mold plates 42, respectively. Upon turning the main lever so that its front arm is lowered and its rear arm raised the several mold members will be shifted into their operative position so that the mold is ready for casting a building 20 block therein and upon turning this lever in the opposite direction the outer wall, side plates and rear mold bar will be simultaneously moved away from the fixed sections of the mold and leave the finished block free to 30 be removed.

For the purpose of securely holding the movable mold members in their closed position, locking means are provided which preferably comprise a dog 53 pivoted on the 35 front arm of the main lever and engaging a beak on its upper arm with an upright row of ratchet teeth 54 on a vertical bar 55 secured to the main frame, a spring 56 connecting the lower arm of the dog with the front arm of the main lever and operating to hold this dog yieldingly in engagement with the ratchet teeth, and a locking lever 57 pivoted on the front arm of the main lever and connected by a link 58 with the upper arm of the dog, as shown in Fig. 1. Upon depressing the front arm of the main lever the dog automatically retains the same in this position by engaging successively with the ratchet teeth, and by simply pressing upwardly on the locking lever the main lever is released preparatory to raising the front arm thereof for opening the mold.

It is desirable to automatically lift and loosen the cast building block after the mold has been opened so as to facilitate the removal of the block from the mold. This is efficiently accomplished by a vertically movable lifting bar 59 which is guided in a way 60 on the main frame and projects 55 with its upper end through an opening 61 in the bottom plate of the mold while its lower end is provided with a pin 62 which engages with a vertical slot 63 formed in a link 64 connected with the front arm of 60 the main lever. The downward movement

of this lifting bar is limited, so that its upper end in the depressed position of the same is flush with the upper side of the bottom plate, by a stop 70 on this bar engaging with a stop 71 on the adjacent part of the main frame. At the end of the downward movement of the lifting bar the pin 62 is arranged in the upper part of the slot 63 in the link 64. During the first part of the mold opening movement of the main lever 75 the same moves independently of the lifting bar 59 without disturbing the latter, during which time the outer wall, side plates and rear mold bar are moved away from the fixed parts of the mold. After the movable parts of the mold have cleared the cast building block the lifting bar ascends and raises the rear part of the same so that it can be subsequently easily removed by hand.

By providing the inner and outer walls of the mold with removable platens the patterns thereof can be changed to suit the length of flange which is desired on the block. For instance in Fig. 1 the pattern on these platens is designed to produce a comparatively long or high flange on the building block while in Fig. 2 the pattern on these platens is designed to produce a comparatively low or short flange on the block. Similarly the horizontal plate of the block 95 can be shortened if desired, as compared with that produced in the mold of Fig. 1, by placing filling pieces 65 in the rear ends of the grooves 28, and attaching an extension piece 66 to the front edge of the rear mold bar 29, as shown in Fig. 2.

When it is desired to provide the horizontal plates of the cast blocks with anchors 21 the latter are put in the mold so that they will become embedded in the plastic mass and lie with their exposed parts flatwise against the outer side of the block which exposed part is however bent to project from the block before the concrete is poured over the blocks and embeds the anchors.

I claim as my invention:

1. A mold for making building blocks comprising a stationary horizontal bottom plate, a mold bar movable toward and from the upper rear part of said bottom plate, a fixed inner wall depending from the front edge of said bottom plate, a fixed bottom flange projecting forwardly from the lower edge of said inner wall, an outer wall movable toward and from said inner wall and flange, and two side plates movable toward and from said bottom plate, mold bar, outer and inner walls and said flange.

2. A mold for making building blocks comprising a stationary horizontal bottom plate, a mold bar pivoted at its rear edge to swing toward and from the rear part of said bottom plate, a fixed inner wall depending from the front end of said bottom plate,

a fixed bottom flange projecting forwardly from the lower end of said inner wall, an outer wall movable toward and from the inner wall and flange and pivotally connected at its lower edge with said flange, two side plates movable toward and from said bottom plate, mold bar, outer and inner walls and bottom flange and pivotally supported at their lower ends, and mold opening and closing means for moving said mold bar, outer wall and side plates simultaneously into and out of their operative position.

3. A mold for making building blocks comprising a stationary horizontal bottom plate, a movable mold bar pivoted at its rear edge to the rear part of said bottom plate, a fixed inner wall depending from the front end of said bottom plate, a fixed bottom flange projecting forwardly from the lower end of said inner wall, an outer wall movable toward and from the inner wall and flange and pivotally connected at its lower edge with said flange, two side plates movable toward and from said bottom plate, mold bar, outer and inner walls and bottom flange and pivotally supported at their lower ends, and mold opening and closing means for moving said mold bar, outer wall and side plates simultaneously into and out of their operative position comprising a main operating lever, upwardly diverging links connecting said lever with said side plates, and connections between said lever and said outer wall and mold bar.

4. A mold for making building blocks comprising a stationary horizontal bottom plate, a mold bar pivoted at its rear edge to the rear part of said bottom plate, a fixed inner wall depending from the front end of said bottom plate, a fixed bottom flange projecting forwardly from the lower end of said inner wall, an outer wall movable toward and from the inner wall and flange and pivotally connected at its lower edge with said flange, two side plates movable toward and from said bottom plate, mold bar, outer and inner walls and bottom flange and pivotally supported at their lower ends, mold opening and closing means for moving said mold bar, outer wall and side plates simultaneously into and out of their operative position comprising a main lever operatively connected with said movable mold members, and means for locking said lever in position when the mold is closed.

5. A mold for making building blocks

comprising a bottom plate, a rear mold bar arranged on the rear part of said bottom plate, an inner wall projecting downwardly from the front end of said bottom plate, a bottom flange projecting forwardly from the lower edge of the inner wall, an outer wall extending from said flange upwardly in front of said inner wall, two side plates arranged on opposite sides of said plate, bar, flange and walls, and means for loosening the building block which has been cast in the mold cavity comprising a lifting bar normally arranged flush with the surface of the mold, and means for raising and lowering said bar.

6. A mold for making building blocks comprising a stationary horizontal bottom plate, a mold bar pivoted at its rear edge to the rear part of said bottom plate, a fixed inner wall depending from the front end of said bottom plate, a fixed bottom flange projecting forwardly from the lower end of said inner wall, an outer wall movable toward and from the inner wall and flange and pivotally connected at its lower edge with said flange, two side plates movable toward and from said bottom plate, mold bar, outer and inner walls and bottom flange and pivotally supporting at their lower ends, mold opening and closing means for moving said mold bar, outer wall and side plates simultaneously into and out of their operative position comprising a main operating lever having a front arm and a rear arm, a rock arm projecting rearwardly from said mold bar, a link connecting said rock arm with the rear arm of said main lever, two upwardly diverging links pivotally connected at their lower ends with the front arm of said main lever and pivotally connected at their upper ends with said side plates, respectively, an intermediate lever connected with its upper arm to said front wall, a link connecting the lower arm of said intermediate lever with the front arm of said main lever, and means for loosening the building block cast in said mold comprising a vertically movable lifting bar adapted to engage its upper side with the underside of the block, a guide for said lifting bar, a stop device for limiting the downward movement of said lifting bar, a link connected at its lower end with said main lever and provided at its upper end with a vertical slot, and a pin arranged on said lifting lever and engaging with said slot.

JAMES G. DAVIS.
